UNITED STATES PATENT OFFICE.

JAMES L. COLE AND BENJAMIN E. SENSE, OF NEW CASTLE, PENNSYLVANIA.

SHADE AND CURTAIN HANGER.

1,356,127.

Specification of Letters Patent.

Patented Oct. 19, 1920.

Application filed April 10, 1920. Serial No. 372,874.

To all whom it may concern:

Be it known that we, JAMES L. COLE and BENJAMIN E. SENSE, citizens of the United States, residing at New Castle, in the county 5 of Lawrence and State of Pennsylvania, have invented certain new and useful Improvements in Shade and Curtain Hangers, of which the following is a specification, reference being had to the accompanying 10 drawings.

This invention relates to certain improvements in shade and curtain hangers, and it is an object of the invention to provide a novel and improved device of this general 15 character which may be readily adjusted to working position without necessitating the use of screws, nails, or the like which would otherwise deface the exposed surface of a window frame or other structure.

It is also an object of the invention to provide a novel and improved device of this character embodying a plurality of suspending members adjustably engaged with a spacing or connecting member and each of 25 which suspending members is provided with either a shade bracket, a curtain pole bracket, or both.

Another object of the invention is to provide a novel and improved device of this 30 general character wherein the spacing or connecting member coacting with the suspending members is provided with means whereby a curtain rod may be applied thereto and supported thereby when desired.

The invention consists in the details of 35 construction and in the combination and arrangement of the several parts of our improved device whereby certain important advantages are attained and the device 40 rendered simpler, less expensive and otherwise more convenient and advantageous for use, as will be hereinafter more fully set forth.

The novel features of our invention will 45 hereinafter be definitely claimed.

In order that our invention may be the better understood, we will now proceed to describe the same with reference to the accompanying drawings, wherein:

Figure 1 is a fragmentary view in elevation, illustrating a shade and curtain hanger constructed in accordance with an embodiment of our invention and in applied 50 position;

Fig. 2 is a horizontal sectional view taken 55 through the structure illustrated in Fig. 1

and taken longitudinally through the spacing or connecting member;

Fig. 3 is a view partly in vertical section and partly in elevation, illustrating in detail a suspending member and the means whereby a curtain pole bracket is operatively supported thereby; and

Fig. 4 is a view similar to Fig. 2 but showing a curtain rod operatively engaged 65 with and supported by the spacing or connecting members.

As disclosed in the accompanying drawings, F denotes the upper portion of a frame for a window or other structure and 70 to which our improved device is applied. Our shade and curtain hanger, as herein disclosed, comprises a pair of suspending members 1 vertically disposed when in applied position and each of said members is provided at its upper end with the rearwardly disposed extension 2 adapted to rest upon the upper edge of the frame. The free end portion of the extension 2 is provided with a depending prong 3 which is adapted to 80 impinge or penetrate the upper surface of the frame F whereby the member 1 is effectively maintained against displacement. The upper portion of each of the members 1, as herein disclosed, is outwardly disposed 85 or inclined, as at 4, in order to compensate for the beading, or the like, which is generally arranged along the upper marginal portion of the top of the frame. 5 denotes an elongated spacing or connecting member 90 preferably comprising a flat metallic strip. The opposite end portions of the member 5 are provided with the elongated slots 6 and through each of which extends an outstanding shank 7 carried by an adjacent member 95 1 and positioned at a desired point intermediate the ends of said member. A winged nut 8 or other suitable clamping member is threaded upon the shank 7 and coacts with the outer face of the member or strip 5 100 whereby the member 1 may be effectively locked in its desired adjustment along the slot 6. By this means, the members 1 may be properly positioned one with respect to the other as required by the occasions of 105 practice.

Carried by the lower portions of the members 1 are the shade brackets 9 of a well known type and with which the shade S, indicated by dotted lines, is adapted to be 110 engaged. As is illustrated in Fig. 1, the brackets 9 are secured to the members 1 by

the removable screws 10 so that said brackets may be readily applied or removed as desired.

Our improved device is also adapted to 5 have secured thereto the curtain pole supporting brackets C for coaction with a curtain pole P, indicated by dotted lines.

Each of the brackets C may be of any 10 preferred construction or design and includes the legs 11 and 12. The legs 11, as disclosed in the accompanying drawings, is uppermost and is provided with an upstanding foot 14 which overlies the outer 15 face of the member or strip 6 and through which the shank 7 is also directed and with which the winged nut or clamping member 8 directly contacts so that the bracket C is effectively secured thereto.

The lower leg 12 of each of the brackets 20 C is also provided with an upstanding foot 15. This foot 15 is provided with the rearwardly directed lug 16 adapted to seat within a suitably positioned opening 17 in the member 1. By this means, the bracket C is 25 effectively maintained in applied position and is substantially carried by a suspension member 1 so that an adjustment of the member 1 may be had longitudinally of the member or strip 5 as the occasions of practice 30 may necessitate.

Each end portion of the member or strip 5 outwardly of the adjacent slot 6 is provided with a threaded opening 18 through which is adapted to be threaded the headed 35 shank or screw 19.

The screws 19 afford means whereby the 40 opposite end portions of a curtain rod R of the well known telescopic type may be secured to the member or strip 5 when desired and whereby said rod may be supported or suspended in working position and without the necessity of marring the woodwork.

It is to be understood that we do not wish 45 to limit ourselves to any particular material from which the several parts comprised in our device may be made although it is preferred that the same be of metal.

From the foregoing description, it is 50 thought to be obvious that a hanger constructed in accordance with our invention is particularly well adapted for use by reason of the convenience and facility with which it may be assembled and operated, and it will also be obvious that our invention 55 is susceptible of some change and modification without departing from the principles and spirit thereof, and for this reason we do not wish to be understood as limiting ourselves to the precise arrangement and 60 formation of the several parts herein shown in carrying out our invention in practice except as hereinafter claimed.

We claim:

1. A device of the character described 65 comprising a pair of suspending members,

a connecting rod having its end portions overlying said members, the opposite end portions of the connecting member being provided with longitudinally disposed slots, clamping means carried by each of the suspending members and disposed through a slot of the connecting member, curtain supporting means carried by said member, and shade brackets carried by the suspending members, said curtain supporting means being held in applied position by the clamping means. 70

2. A device of the character described comprising a pair of suspending members, a connecting rod having its end portions 80 overlying said members, the opposite end portions of the connecting member being provided with longitudinally disposed slots, clamping means carried by each of the suspending members and disposed through 85 a slot of the connecting member, shade brackets carried by the suspending members, said clamping means comprising a coacting shank and nut, and curtain supporting means carried by the suspending members, said curtain supporting means being held in applied position by the clamping means. 90

3. A device of the class described comprising a pair of suspending members, a 95 connecting member coacting therewith, the end portions of said connecting member overlying the suspending members, the end portions of the connecting member having slots, an outstanding shank carried by each 100 of the suspending members and disposed through the slot, a clamping member engaged therewith, and a curtain pole bracket provided with a leg through which the shank of the suspending member passes and 105 with which the clamping member coacts. 100

4. A device of the class described comprising a pair of suspending members, a connecting member coacting therewith, the end portions of said connecting member overlying the suspending members, the end 110 portions of the connecting member having slots, an outstanding shank carried by each of the suspending members and disposed through the slot, a clamping member engaged therewith, and a curtain pole bracket provided with a leg through which the shank of the suspending member passes and with which the clamping member coacts, 115 said curtain rod bracket being also provided with a second leg, said second leg having a rearwardly facing lug, the suspending member being provided with an opening to receive said lug. 120

5. A device of the character described 125 comprising a pair of suspending members, a connecting rod substantially straight from one end to the other having its end portions overlying said members, the opposite end portions of the connecting member being 130

provided with longitudinally disposed slots, clamping means carried by each of the suspending members and disposed through a slot of the connecting member, and shade
5 brackets carried by the suspending members, said connecting member outwardly of the suspending members being provided

with openings, and securing members engageable therein.

In testimony whereof we hereunto affix 10
our signatures.

JAMES L. COLE.
BENJAMIN E. SENSE.
